UNITED STATES PATENT OFFICE.

GEORGE S. HICE, OF BROOKLYN, NEW YORK.

FASTENER.

1,163,088.

Specification of Letters Patent.

Patented Dec. 7, 1915,

Application filed August 17, 1914. Serial No. 357,029.

To all whom it may concern:

Be it known that I, GEORGE S. HICE, a citizen of the United States, residing at 696 to 710 Jamaica avenue, Brooklyn, in the 5 county of Kings and State of New York, have invented certain new and useful Improvements in Fasteners, of which the following is a specification.

This invention relates to improvements 10 in fasteners, particularly such as are intended for use in connecting a collar to the neck band of a shirt.

It is an object of my invention to produce a fastener which will have all the advantages of the ordinary collar button, but 15 without the disadvantages thereof.

In the accompanying drawings, which are to be taken as a part of this specification and in which I have shown a preferred 20 form of the embodiment of the invention,

Figure 1 is a vertical sectional view through a neck band and a turn-over collar, and through a fastening device embodying the invention, which connects the neck band 25 and the collar. Fig. 2 is an elevation of the attaching device, and Fig. 3 is an edge view of the same.

Referring to the numerals on the drawings there is shown in Fig. 1 the neck band 30 4 of a shirt, which is provided with the usual button-hole 5, and 6 indicates a collar, shown in the present instance as a turn-over collar which is secured to the neck band 4 at the rear by means of my improved fas-

35 tening device. This fastening device comprises a single piece of sheet metal, which may be conveniently stamped out into form and which comprises an oblong base 7 curved from end to end as shown in Fig. 3. From this base extends a neck or connect- 40 ing piece 8, which is preferably bent as shown and which takes a generally down- 45 ward course away from the base 7, consider- ing the base 7 as the top of the device. At the end of the neck 8 there is what may be 50 termed a head 9, which has a stamped out projecting part or lug 10. In use, the head 9 is inserted through the button-hole 5 of the neck band, with the base 7 on the inside 55 and with the curve of the base 7 coinciding with the curve of the neck band. The neck

or connecting part 8 extends through the button-hole 5 of the neck band and also through the button-hole 11 of the collar 6, the offset provided by the band in the connecting portion allowing for the thickness of the neck band and collar so that there is no tendency for the attaching device to tilt. The head of the device 9 extends down between the folded portions of the collar, and 60 the projecting part 10 acts as a spacing member to keep the outer fold 12 of the collar away from the inner fold thereof, so as to provide larger tie space. A necktie is indicated at 14 in Fig. 1, and it will be seen 65 that the lower edge of this tie will bear against the connecting part or neck 8 of the device, which being of metal and of course smooth will offer but little interference to the movement of the necktie in the act of 70 tying the same. Obviously the position occupied by the neck 8 is at the point of the most decided bend in the collar, and to provide a smooth surface here for the tie to move over means to minimize the sticking 75 of the necktie in the act of tying it.

Inasmuch as many changes could be made in the above construction, and many apparently wide different embodiments of my invention could be made without departing 80 from the scope thereof, it is intended that all matter contained in the above description or shown in the accompanying drawings shall be interpreted as illustrative and not in a limiting sense. It is also to be un- 85 derstood that the language used in the following claims is intended to cover all the generic and specific features of the invention herein described and all statements of the scope of the invention which, as a matter 90 of language, might be said to fall therebetween.

I claim:

1. A device of the kind described, comprising a metal blank having an oblong 95 curved portion, a laterally extending neck offset therefrom, a head connected to said neck and a spacing lug on said head, said lug being slightly smaller than said head and of approximately the same outline. 100

2. A device of the kind described, comprising a metal blank having an oblong

curved portion, a laterally extending neck offset therefrom, an enlargement connected to said neck, said enlargement provided with a spacing means arranged centrally 5 thereof and being of approximately the same outline as said enlargement.

In testimony whereof I affix my signature in presence of two witnesses.

GEORGE S. HICE.

Witnesses:
